HAIR TRIMMING RAZOR OR THE LIKE

Armando O. Mauro, 927 Broxton Ave.,
Los Angeles 24, Calif.

Filed July 15, 1963, Ser. No. 75,798

Term of patent 14 years

(Cl. D22—3)

FIGURE 1 is a perspective view of a hair trimming razor or the like, showing my new design;

I claim:

The ornamental design for a hair trimming razor or the like, substantially as shown.
